STEEL PLATE CLAMP

Ray G. Boree and James A. Townsend, Jacksonville, Fla.; said Townsend assignor to said Boree

Application September 2, 1943, Serial No. 500,986

3 Claims. (Cl. 294—104)

The present invention relates to new and useful improvements in steel plate clamps for use particularly in shipyards, et cetera, and has for its primary object to provide, in a manner as hereinafter set forth, a device of this character comprising novel means for firmly gripping the plates.

Other objects of the invention are to provide a clamp of the aforementioned character which will be comparatively simple in construction, strong, durable, highly efficient and reliable in use, compact, and which may be manufactured at low cost.

All of the foregoing, and still further objects and advantages of the invention will become apparent from a study of the following specification, taken in connection with the accompanying drawings, wherein like characters of reference designate corresponding parts throughout the several views, and wherein:

Figure 1 is a view in side elevation of a steel plate clamp constructed in accordance with the present invention.

Figure 2 is a plan view of the device.

Figure 3 is a cross-sectional view, taken substantially on the line 3—3 of Figure 1.

Figure 4 is a view in longitudinal section through the forward portion of the device.

Figure 5 is a detail view in perspective of the pivotally and slidably mounted jaw-actuating bar.

Figure 6 is a detail view in perspective of the toothed stationary jaw and the supporting web therefor.

Figure 7 is a detail view in perspective of one of the links between the pivoted jaw and the bar shown in Figure 5.

Referring now to the drawings in detail, it will be seen that the embodiment of the invention which has been illustrated comprises a pair of spaced, opposed, duplicate, elongated plates 1 of suitable dimensions and metal. Rivets or the like 2, 3 and 4 secure the plates 1 together in spaced relation. It will be observed that the rivets 2 are mounted in one end portion of the plates 1. Slots 5 extend longitudinally into the plates 1 from the other ends thereof.

Welded between the plates 1 adjacent one of the longitudinal walls of the slots 5 is a metallic web 6. Removably mounted on the web 6 for engagement with a plate in the slots 5 is a toothed stationary jaw 7. A screw 8 secures the jaw 7 to the web 6. Welded on one end portion of the web 6 is a stop 9 for the jaw 7.

Extending between the plates 1 adjacent the

other longitudinal walls of the slots 5 is a removable pin 10. Journalized on the pin 10 is a pivoted jaw 11 in the form of a toothed eccentric which is cooperable with the stationary jaw 7 for firmly gripping and retaining a steel plate in said slots 5. Spacers 12 are provided between the pivoted jaw 11 and the plates 1, the pin 10 passing through said spacers.

Pivotally and slidably mounted on the pin 2 for operation between the plates 1 is a metallic bar 13. The bar 13 has formed therein, at an intermediate point, a longitudinal slot 14 which accommodates the pin 2. In its outer end portion, the bar 13 is further provided with a shackle opening 15. Links 16 operatively connect the bar 13 to the pivoted jaw 11. A pin 17 pivotally connects the links 16 at one end to the inner end portion of the bar 13. The other end portions of the links 16 are pivotally connected by a pin 18 to the jaw 11.

It is thought that the operation of the clamp will be readily apparent from a consideration of the foregoing. Briefly, the members 1 are engaged with the steel plate to be lifted or moved, the slots 5 receiving said steel plate. The pivoted jaw 11 readily swings to open position to facilitate engaging the clamp with the steel plate. When the bar 13 is pulled in a direction away from the plates 1, the pivoted jaw 11 is swung toward closed position through the medium of the links 16. Thus, the steel plate is firmly gripped between the toothed jaws 11 and 7. The greater the weight of the steel plate, the tighter will be the grip of the clamp thereon. It will be observed that the construction and arrangement is such that the operating means for the pivoted jaw 11 is protected between the plates 1 which thus constitute a housing for preventing these elements from striking or fouling objects with which the clamp may come in contact. The screw 8 permits the jaw 7 to be readily removed for replacement. Also, the pivoted jaw 11 may be readily removed by removing the pins 10 and 18. Spacers 19 are provided between the bar 13 and the plates 1, the rivet 2 passing through said spacers. Forwardly of the pin 4, a spacing web 20 extends between the plates 1.

It is believed that the many advantages of a steel plate clamp constructed in accordance with the present invention will be readily understood, and although a preferred embodiment of the device is as illustrated and described, it is to be understood that changes in the details of construction and in the combination and arrange-

ment of parts may be resorted to which will fall within the scope of the invention as claimed.

What is claimed is:

1. A clamp of the character described comprising a pair of spaced, opposed plates having slots extending therewith from one edge thereof for the reception of an object to be moved, a stationary jaw mounted between the plates, a pivoted jaw mounted between the plates and cooperable with the stationary jaw for gripping the object in the slots, a bar pivotally and slidably mounted between the plates, and links between the plates operatively connecting said bar to the pivoted jaw.

2. A clamp of the character described comprising a pair of spaced, opposed metallic plates having slots extending therewith from one end thereof for the reception of an object to be moved, a web extending between the plates adjacent one side of the slots, a stationary jaw removably mounted on the web, a pivoted jaw mounted for swinging movement between the plates on the other sides of the slots and cooperable with the stationary jaw, a bar pivotally and slidably mounted between the plates, and links connect-

ing the pivoted jaw to said bar for actuation thereby.

3. A clamp of the character described comprising a pair of spaced, opposed, duplicate, elongated metallic plates having slots extending longitudinally therewith from one end thereof for the reception of an object to be moved, rivets extending between the plates for securing said plates together in spaced relation, a web extending between the plates adjacent one side of the slots, a toothed, stationary jaw mounted on said web, a screw threadedly mounted in the web and connected to the stationary jaw for removably securing said stationary jaw on the web, a stop for the stationary jaw on the web, a removable pin extending between the plates adjacent the other sides of the slots, a toothed eccentric jaw pivotally mounted on said pin and cooperable with the stationary jaw for gripping an object in the slots, a bar pivotally and slidably mounted on one of the rivets and operable between the plates, and links between the plates operatively connecting said bar to the pivoted jaw.

RAY G. BOREE.
